(57) **CLAIM**

We claim the ornamental design for a sensor housing for use with post top luminaires, as shown and described.

DESCRIPTION

FIG. 1 is a top perspective view of a sensor housing for use with post top luminaires in accordance with the present design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

The broken lines show portions of the sensor housing for use with post top luminaires that form no part of the claimed design.

1 Claim, 7 Drawing Sheets
